UNITED STATES PATENT OFFICE

WILLIAM G. FORBES, OF NEW YORK, N. Y.

HIGH SPEED CIGARETTE CUTTER

Application filed August 20, 1926. Serial No. 130,366.

My invention relates to cut-off mechanism for cigarette machines wherein the tobacco is automatically fed into a continuous strip of paper to form a continuous closed tobacco tube, which tube is cut into the required lengths to form the cigarettes.

This application is a division, in part, of my copending application filed Jan. 26, 1926, Serial Number 83,831.

10 My invention more particularly relates to a method of cutting a cigarette tube, or tubes, and to a high speed cutter which will materially increase the output of such a cigarette machine, with no additional expense other than substituting my high speed rotary cutter and accessory parts, for the ordinary rocking or reciprocating rotary cutter now in common use.

20 My invention further relates to cutting the cigarette tube with a sheer cut. My invention further relates to a rotary knife having one or more cutting edges, cooperating with one or more reciprocating ledger plates, the reciprocation of the ledger plates being controlled by the rotation of the knife, to cut cigarettes from one or more cigarette tubes.

25 Objects and advantages of the invention will be set forth in part hereinafter and in part will be obvious herefrom, or may be learned by practice with the invention, the same being realized and attained by means of the instrumentalities and combinations pointed out in the appended claims.

35 The invention consists in the method, novel parts, constructions, arrangements, combinations, articles of manufacture, and improvements herein shown and described.

40 The accompanying drawings, referred to herein and constituting a part hereof, illustrate one embodiment of the invention, and together with the description, serve to explain the principles of the invention.

Of the drawings:—

45 Fig. 1 is a fragmentary plan view of one form of my high speed cigarette cutter and that portion of a cigarette machine upon which it is mounted;

50 Fig. 2 is a fragmentary, vertical section on the line 2—2 of Fig. 1;

Fig. 3 is a plan view of one form of curved knife which I preferably employ;

Fig. 4 is a perspective view of the cutter disc showing the peripheral arcuate eccentric notch or recess, and one of the cam grooves;

Fig. 5 is a perspective view of the curved clamping plate;

Fig. 6 is a diagrammatic view of the cutter disc and knife cutting one cigarette tube;

Fig. 7 is a fragmentary detail view showing an automatic sharpening device to sharpen the rotary knife on each revolution;

Fig. 8 is a detail of a modification.

55 My invention is directed to providing a novel and useful cigarette cut-off mechanism adapted to cut cigarette lengths from an axially moving cigarette tube or rod. The mechanism of the invention provides an exceedingly simple, inexpensive and efficient 60 cut-off mechanism which is adapted to sever cigarettes at speeds very much higher than is possible with existing machines. In addition to its greatly increased speed of operation, the mechanism provides a clean shear 65 cut across the axis of moving cigarette rod 70 without the slightest retardation or buckling of the rod.

75 One of the broad objects of my invention is to provide an efficient cut-off mechanism 80 operating by purely rotary movement as distinguished from known machines wherein a reciprocating, rocking or other translatory movement is imparted to the cutting blade in order to make a straight line cut across in 85 moving rod. In accordance with this object, the invention provides a knife or blade adapted to revolve in a circular path, while the cigarette rod is moved axially across the face 90 of the circle described by the knife. The cutting edge of the knife itself is so shaped or positioned with respect to the movement of revolution and with respect to the moving cigarette rod, that said cutting edge or element progresses along the line of movement 95 of the cigarette rod during the cutting action although the bodily movement of the knife itself is purely one of revolution. Accordingly, the knife may be revolved at exceedingly high speeds and will operate efficiently at 100

such speeds because there is no rocking or stopping and starting movement or other eccentricity in the operation of the device. A further object of the invention is to provide novel and useful means for sharpening or grinding the cutting edge of the knife, said grinding means being adapted to cooperate with the normal movement of the knife for cutting operation.

10 Another object of the invention is to provide a novel and useful form of knife or cutter blade which is adapted to cooperate with the novel cut-off mechanism hereinbefore described.

15 By my invention, I form a simple and economical high speed cigarette cutter, which will cut approximately a thousand or more cigarettes a minute from one cigarette tube, and approximately two thousand or more 20 cigarettes per minute from two cigarette tubes, thereby greatly increasing the output of the cigarette machine and in many instances quadrupling it.

It will be understood that the foregoing 25 general description and the following detailed description as well, are exemplary and illustrative of the invention, but are not restrictive thereof.

30 In the illustrative embodiment of my invention shown in the drawings, to which my invention is not to be limited, except as defined by my claims, 1 is a cutter disc keyed on the shaft 2 by means of the keys 3 and 4 (Figs. 1 and 2). This shaft is journaled in 35 a sleeve 5 mounted in an adjustable bearing 6, the bearing being provided with a screw-threaded boss 7, with which cooperates an adjusting screw 8 passing through the bearing 9 which is secured, by the screw 10, 10 to the plate 11. On the end of this 40 screw 8 is secured in any suitable manner, as by the pin 12, an actuating handle 13. The plate 11 is provided with parallel slots 14, 14 with which cooperate the bolts 15, 15, 45 the arrangement being such that after the cutter disc 1, with the sleeve 5 and adjusting bearing 6 has been properly adjusted, it can be locked in the adjusted position by screwing up the nuts 60, 60 cooperating with the 50 bolts 15, 15. The heads (not shown) of the nuts 15, 15 can be passed through the enlarged openings 61, 61 so that they can be located below the plate 11. On the axle 2, I mount a collar 16 by means of a key 17.

55 On the periphery of the cutter disc 1, I mount a curved knife 18 in the peripheral arcuate eccentric notch or recess 19. This knife may have either a single or double cutting edge depending upon whether or not 60 it is to cut cigarettes from one or two cigarette tubes fed to it. In my preferred construction, the knife 18 is provided with two cutting edges 20, 21 and with two holes 22, 22 to register with the holes 23, 23 in the 65 curved clamping plate 24, which is mounted

above the curved knife 18. The clamping screws 25, 25 (Fig. 1) pass through the holes 23, 23 and 22, 22 and engage with screw-threads in the cutter disc 1. This cutter disc is also provided with one or two eccentric cam grooves 26, 27, for a purpose to be more fully hereinafter described. When the knife is provided with two cutting edges, it is, in effect, a double knife.

70 Mounted on the cigarette machine are two ledger plate bearings 28, 28 within which reciprocate the reciprocating ledger plates 29, 29 each ledger plate being provided with a blade opening 30. Each ledger plate is also provided with means for permitting the cutter disc to control its reciprocation. I have shown for example, each reciprocating ledger plate 29 provided with a pin 31 upon which is mounted a roller 32, the roller cooperating with its own cam groove 26 or 27 85 in the cutter disc 1, as the case may be.

If my cutter is to be used simply to cut cigarettes from a single cigarette tube 33, this tube or rod is fed over a feed wheel 34 and through one of the reciprocating ledger 90 plates 29 at high speed. The cutter disc 1, rotating at high speed, causes the cutting edge 20, for example, of the knife 18 to pass into the knife openings 30 in the reciprocating ledger plate shown, for example, in sections in Fig. 1. The knife 18, revolving at high speed passes through and completely 95 severs the cigarette tube to form a cigarette. During the cutting of the cigarette tube 33 the active cutting edge of the knife 18 has 100 traveled from the point 35 to the point 36 (Fig. 6). This exactly corresponds to the forward movement of the cigarette tube thereby preventing any buckling or marring of the cigarette tube 33 or the severed cigarettes 45, 105 45. During this travel of the cigarette tube 33, from point 35 to point 36, the reciprocating ledger plate 29 moves with and at the same speed as the cigarette tube 33, so that 110 there is a positive and sheer cut of each cigarette from the tube, which enhances the appearance of the cigarettes and adds to their marketability.

The cut cigarettes then drop upon the deflector plate 40 and onto a traveling belt 41, 115 the belt moving preferably somewhat faster than the cigarette tube 33 so as to separate the cut cigarettes, as shown in Fig. 1. These cut cigarettes fall into a hopper 42 and then pass to a packing machine 43 which is no 120 part of my invention.

So far I have described my invention simply as cutting cigarettes from a single cigarette tube, the capacity of the cutter, operating with one cigarette tube, being approximately a thousand cigarettes a minute. In my preferred construction, which is illustrated in the drawings, I feed a plurality of cigarette tubes, two cigarette tubes being shown 33, 33, over the feed rolls 34, 34, one 125

on either side of the cutter disc 1. In this preferred form both cutting edges 20 and 21 of the knife 18 are brought into play each cutting edge cooperating with its own blade opening 30 in its own reciprocating ledger plate 29, the reciprocation of each ledger plate being controlled by the roller 32 mounted upon it, cooperating with its own cam groove 26 or 27 as the case may be.

The cigarette tubes 33, 33 may be fed from a single filling machine, or from two such filling machines, or any form of cigarette machine which will form continuous cigarette tubes and feed them at high speed to my cutter.

The cut cigarettes from the second cigarette tube 33 fall upon the other deflecting plate 40 and thence onto the other belt 41 which is run at the same speed as the first belt 41 so as to separate the cutter cigarettes. Cut cigarettes from both the cigarette tubes 33, 33 may be permitted to fall into the hopper 42 and then pass to the machine 43, or one belt 41 may feed the cut cigarettes 45 into the compartment 46 of the hopper 42, while the cut cigarettes 45 from the other cigarette tube 33, will fall into the compartment 47 of the hopper 42. In this manner, the cigarettes from each cigarette tube can be separately packed, if for any reason this is necessary or desirable.

In Fig. 7 I have shown an automatic sharpener to automatically sharpen the knife 18, two of these sharpeners being used to sharpen both cutting edges 20 and 21 (only one shown in the drawing).

On the stud 63 I pivotally mount an arm 64 in any suitable manner, as by bending the end 65 of the arm around the stud 63 and loosely securing it in this position by the screw 66. On the free end 67 of the arm is mounted any suitable sharpening surface as for example a block of carborundum 68 held in the seat 69 by the set screw 70.

It will be clear that on each revolution of the cutter disc 1 the edge of the blade of the knife 18 will engage with this sharpener 68 and cause the arm 64 to rock on the pivot stud 63 against the action of the spring 71.

As soon as the knife disengages the sharpener the spring 71 will cause the arm to snap back to the stop 72, ready to again sharpen the blade on the next revolution of the cutter disc. The cutter, for the other cutting edge 21 (not shown) operates in the same manner.

The invention in its broader aspects is not limited to the specific mechanisms shown and described, but departures may be made therefrom within the scope of the accompanying claims without departing from the principles of the invention and without sacrificing its chief advantages.

What I claim is:

1. A cigarette cut-off mechanism including

in combination a knife revolving in a circular path and having a cutting edge eccentric to the center of said path, means for feeding a cigarette rod across the face of the circle described by the knife and in a plane intersected by the cutting edge of the knife, knife grinding means mounted adjacent said circular path and means for yieldingly maintaining the grinding means in continuous grinding contact with the eccentric cutting edge of the knife during the passage of the knife by the grinding means.

2. A cigarette cut-off mechanism including in combination a rotatable knife-supporting body, a knife projecting from the plane of rotation of said body, means for feeding a cigarette rod across the face of the circle described by the knife, different portions of the knife edge being positioned at different distances from the center of said circle, whereby the cutting edge of the knife travels with the cigarette rod during the cutting thereof, a movable ledger plate, and means for maintaining said ledger plate in shearing contact with the knife during the cutting operation.

3. A cigarette cut-off mechanism including in combination a rotatable knife-supporting body, a knife projecting from the plane of rotation of said body, means for feeding a cigarette rod across the face of the circle described by the knife, different portions of the knife edge being positioned at different distances from the center of said circle, whereby the cutting edge of the knife travels with the cigarette rod during the cutting thereof, a reciprocable ledger plate actuated from the drive shaft of the knife-supporting body, and means for reciprocating said ledger plate in synchronism with the cutting movement of the knife.

4. A cigarette cut-off mechanism including in combination a rotatable knife-supporting body, a knife projecting from the plane of rotation of said body, means for feeding a cigarette rod across the face of the circle described by the knife, different portions of the knife edge being positioned at different distances from the center of said circle, whereby the cutting edge of the knife travels with the cigarette rod during the cutting thereof, knife grinding means mounted adjacent the circle described by the knife and means for maintaining the grinder in continuous grinding contact with the cutting edge of the knife during the passage of the knife by the grinding means.

5. A cigarette cut-off mechanism including in combination a rotatable knife-supporting body, a knife projecting from the plane of rotation of said body, means for feeding a cigarette rod across the face of the circle described by the knife, different portions of the knife edge being positioned at different distances from the center of said circle, whereby

the cutting edge of the knife travels with the cigarette rod during the cutting thereof, said knife being tapered axially with respect to the rotatable body, knife grinding means mounted adjacent the circle described by the knife and means for maintaining the grinder in continuous grinding contact with the cutting edge of the knife during the passage of the knife by the grinding means.

10 In testimony whereof, I have signed my name to this specification.

WILLIAM G. FORBES.
